[57] CLAIM

The ornamental design for a soft form radio, as shown and described.

DESCRIPTION

FIG. 1 is a front elevational view of a soft form radio showing my new design;

FIG. 2 is a rear elevational view thereof;

FIG. 3 is a right side elevational view, the left side being a mirror image thereof;

FIG. 4 is a top plan view thereof;

FIG. 5 is a bottom plan view thereof; and,

FIG. 6 is a front, right side, and bottom perspective view thereof.

FIGS. 2 and 4-6 are on an enlarged scale.
